UNITED STATES PATENT OFFICE.

ALBERT N. MARQUIS, OF CHICAGO, ILLINOIS.

DEVICE FOR PERMITTING ADJUSTMENT OF NECKTIES.

1,128,800.

Specification of Letters Patent. Patented Feb. 16, 1915.

Application filed March 15, 1909. Serial No. 483,523.

To all whom it may concern:

Be it known that I, ALBERT NELSON MARQUIS, a citizen of the United States, and a resident of Chicago, in the county of Cook 5 and State of Illinois, have invented certain new and useful Improvements in Devices for Permitting Adjustment of Neckties, of which the following is a specification.

This invention relates to apparel and relates particularly to devices adapted for use 10 in connection with "turn-down" collars, to permit neckties to be quickly and conveniently adjusted endwise therein, when the collars are "on".

15 The object of the invention is to provide means in connection with a turn-down collar to prevent the collar from pinching and binding upon the necktie when the tie is placed therein and the collar "put on", 20 thus permitting the necktie to be easily pulled endwise to adjust the ends to proper lengths for tying, which, as is well known, is now the cause of frequent and great annoyance. To this end, a device of my invention, which, for purposes of convenient reference, will be designated herein as a 25 "slip", comprises the various features and details of construction hereinafter described and claimed.

30 In the accompanying drawing, in which my invention is fully illustrated—Figure 1 is a perspective view of a collar to which one of my improved necktie slips is applied, said collar and necktie slip being both 35 broken away, in part, to show the construction and operation of said slip. Fig. 2 is a front view of my improved slip, showing a necktie in position therein, preparatory to inserting the same into the fold of a collar; 40 and Fig. 3 is a sectional view through said collar, slip and necktie, on an enlarged scale.

Referring now to the drawing, A designates, as a whole, a usual type of turn-down collar.

My improved slip, designated as a whole 45 by B, is made of suitable material, preferably silk or satin cloth or fabric, of such character that neckties will adhere thereto as little as possible, and comprises two plies 1 and 2, secured together at one edge and 50 shaped to conform, in a general way, to the shape of the collar A. Said slip B is designed and adapted to be inserted between the folds of the collar A and the necktie, 55 shown at C, is adapted to be inserted between the plies 1 and 2 of said slip.

It is found in practice, that the anti-friction character of the slip B reduces the friction between the said slip and the tie C to such an extent that said tie may be pulled 60 endwise to adjust its ends to proper lengths for tying with comparative ease. To still further reduce the frictional resistance to the endwise movement of said tie, the plies 1 and 2 of the slip B are preferably spaced 65 apart, as by a strip 3 of braid or the like, inserted between the connected edges of said plies 1 and 2, which will operate to prevent, 70 to a large extent, the collar and slip from pinching and binding upon the necktie.

I claim:

A slip comprising plies of suitable anti-friction material connected at their upper edges and adapted to be inserted between the folds of a turn-down collar so that the necktie will pass between the plies thereof and a spacing strip attached to the connected edges of said plies, substantially as described.

In testimony, that I claim the foregoing 80 as my invention, I affix my signature in presence of two subscribing witnesses, this 12th day of March, A. D. 1909.

ALBERT N. MARQUIS.
